UNITED STATES PATENT OFFICE.

ALBERT B. KNIGHT, OF FAIRMONT, WEST VIRGINIA.

GLASS-HEATING BURNER.

1,109,131.

Specification of Letters Patent.

Patented Sept. 1, 1914.

Application filed August 15, 1912. Serial No. 715,142.

To all whom it may concern:

Be it known that I, ALBERT B. KNIGHT, a citizen of the United States, residing at Fairmont, in the county of Marion and State 5 of West Virginia, have invented certain new and useful Improvements in Glass-Heating Burners, of which the following is a specification.

The present invention relates to means for 10 heating the ends of tumblers or glasses after the same have been cracked off and ground to melt the same and provide a smooth surface.

An important object of the invention is to 15 provide novel heating means of the above mentioned character, which will properly melt the ends of the tumblers or glasses without discoloring them.

A further object of the invention is to 20 provide heating means of the above mentioned character, which is well adapted to be used in connection with a rotatable structure which carries tumblers or glasses.

A further object of the invention is to 25 provide a device of the above mentioned character, which is simple in construction, cheap to manufacture, and durable.

Other objects and advantages of the invention will be apparent during the course 30 of the following description.

In the accompanying drawings forming a part of this specification, and in which like numerals are employed to designate like parts throughout the same, Figure 1 is a 35 side view of the device, shown in connection with means to move the articles to be heated, Fig. 2 is a plan view of my improved heating means or burner, and, Fig. 3 is a vertical sectional view taken on line 3—3 of Fig. 2, parts being shown in elevation.

In the drawings wherein for the purpose of illustration, I have shown a preferred embodiment of my invention, the numeral 4 designates a stationary support or base, 45 upon which is mounted a stationary up-standing shaft 5.

Mounted upon the base 4 is a stationary ring 6.

The numeral 7 designates a plurality of 50 spindles which are rotated about the ring 6 and have slidable engagement therewith. The spindles 7 are rotatably mounted through brackets 8, which straddle pinions 9, rigidly attached to the spindles. These 55 brackets are provided near their lower ends with inwardly extending radial arms 10,

which are connected with a gear 11. The gear 11 is rotatably mounted upon the stationary shaft 5.

The numeral 12 designates a stationary gear which is rigidly connected with the shaft 5 and engages the pinions 9. The gear 11 receives its rotation from a gear 13, which is rigidly connected with an upstanding rotatable shaft 14. This rotatable shaft 65 is journaled through portions of the base 4 and carries a worm-wheel 15, as shown. The worm-wheel 15 is driven by a worm 16, which is rotated by a motor 17. It is thus seen that when the motor 17 is in operation, 70 the gear 13 will rotate the gear 11, which causes the spindles 7 to rotate about the stationary ring 6, said pinions also rotating upon their longitudinal axes by virtue of the fact that the pinions 9 travel in engagement with the stationary gear 12. Rigidly connected with the upper ends of the spindles 7 are trays 18 or the like, upon 75 which are placed the tumblers or glasses to be heated. Disposed inwardly of the trays 80 18 is a cylinder 19, which may be formed of fire-brick or other heat resisting material.

Disposed above the trays 18 and suitably spaced from the same is a substantially semi-annular relatively large burner 20, 85 which is in the form of a conduit with both ends thereof closed, as shown. This burner conduit is preferably formed square in vertical cross-section, as shown, and is provided upon its lower horizontal flat wall 90 with perforations 21, which are distributed over the entire area of said wall. Attention is called to the fact that these perforations are comparatively small and that there is a great number of them. The num- 95

eral 22 designates a gaseous fuel receiving shell, which is approximately relatively large semi-cylindrical. Connected with this shell 2 are pipes 23, which are radially disposed and have suitable connection with the conduit 20, at equi-distantly spaced points as shown. Attention is called to the fact that there is a great number of these pipes 23, which is an important feature of the invention, as by this means alone can the 100 gaseous fuel be properly supplied to the burner conduit 20, so that a flame may be had which will not discolor the articles of glass to be heated. Connected with the pipes 23 are valves 24, which allow the 105 gaseous fuel to be properly adjusted in each.

The numeral 25 designates an air supply pipe, which leads into the shell 22. Extending into the pipe 25 is a gas supply pipe 26, which is provided with perforations 27.

5 The pipes 25 and 26 supply air and gas respectively to the shell 2, wherein a properly carbureted gas is formed, to be subsequently discharged through the pipes 23.

In the operation of the machine the tumblers 28 are placed in the trays 18 as the same rotate past the rear portion of the machine. These tumblers are now carried past the front portion of the machine and under the burner conduit 20. The gas escaping 10 through the perforations 21 provides a suitably hot flame which will properly melt the ground end of the tumbler by the time the same is moved beneath the burner conduit 20 for the entire length of the same, without 15 in any way discoloring the glass.

I am aware that attempts have heretofore been made to construct burners for this purpose out of clay or other plastic material. These burners are very objectional for many 20 reasons, particularly as they crack from being overheated and do not last long. As far as I am aware no burners of this type have heretofore been constructed of iron or any other suitable metal, owing to the fact that 25 these burners when constructed of metal, would discolor the glass. I have discovered that by the peculiar construction of my burner, particularly the provision of the large number of perforations in the burner 30 conduit and the large number of supply pipes, that my burner may be advantageously employed to heat the tumblers without discoloring them.

I wish it understood that the form of my 35 invention herewith shown and described is to be taken as a preferred example of the same and that certain changes in the shape,

size, and arrangement of parts may be resorted to without departing from the spirit of the invention or the scope of the subjoined claim.

Having thus described my invention, I claim:

In apparatus of the character described, the combination with an approximately 50 semi-annular relatively large metallic burner conduit having a substantially horizontal flat bottom wall provided with relatively fine perforations, of a plurality of fuel supply conduits connected with one 55 side of the approximately semi-annular metallic burner conduit and leading into the same at substantially equi-distantly spaced points to supply gas therein for maintaining a uniform pressure of the gas throughout all portions of the burner conduit, a fuel supply chamber arranged substantially concentric with relation to the approximately semi-annular metallic burner conduit and connected with the fuel supply 60 conduits, means for supplying air to the fuel supply chamber, means to supply gas to the fuel supply chamber, a bodily rotatable carrier arranged near and below the approximately semi-annular burner conduit, a plurality of devices connected with the bodily 65 rotatable carrier to move therewith and hold tumblers or the like below and in proximity to the perforated bottom wall of the metallic burner conduit, and means to rotate the 70 devices upon their longitudinal axes during their bodily rotation with the carrier.

In testimony whereof I affix my signature in presence of two witnesses.

ALBERT B. KNIGHT.
